UNITED STATES PATENT OFFICE.

ABEL P. HOLCOMB, OF EAST RANDOLPH, NEW YORK.

WASHING-MACHINE.

1,100,240.

Specification of Letters Patent. Patented June 16, 1914.

Application filed September 9, 1912. Serial No. 719,485.

To all whom it may concern:

Be it known that I, ABEL P. HOLCOMB, a citizen of the United States, residing at East Randolph, in the county of Cattaraugus 5 and State of New York, have invented a new and useful Washing-Machine, of which the following is a specification.

One object of the present invention is to provide, in a washing machine having a reciprocating compression member, means whereby the clothes, when acted upon by the compression member, will be rolled upon an axis, thereby presenting different portions of the clothes successively to the action of 10 the compression member.

Another object of the invention is to provide novel means whereby the water, when squeezed out of the clothes by the action of the compression member, will be prevented 15 from spattering about.

Another object of the invention is to provide a washing machine of the type above specified having a novel arrangement of elements whereby the water may pass readily 20 out of the clothes when the same are acted upon by the compression member.

With the foregoing and other objects in view which will appear as the description proceeds, the invention resides in the combination and arrangement of parts and in the details of construction hereinafter described 30 and claimed, it being understood that changes in the precise embodiment of invention herein disclosed can be made within 35 the scope of what is claimed without departing from the spirit of the invention.

In the accompanying drawing Figure 1 shows the invention in vertical longitudinal section; Fig. 2 is a vertical transverse section upon the line A—B of Fig. 1, looking in the direction of the arrow 2; Fig. 3 is a vertical transverse section upon the line 40 A—B of Fig. 1, looking in the direction of the arrow 3; and Fig. 4 is a top plan, parts 45 being broken away.

In carrying out the invention there is provided a tub, preferably of rectangular contour, the tub being supported by legs 2, or in any suitable manner. The tub 2 comprises an inclined bottom 3, and an end wall 4 provided at its upper edge and adjacent its ends with notches 5, there being a bead 4^a located in the angle defined by the bottom 3 and the end wall 4, the bead 4^a constituting a means for supporting the end wall, and for connecting the same with the bot-

tom, and an end wall 6, the upper edge of which, denoted by the numeral 7, constitutes a wringer support, the end wall 6 being equipped adjacent the lowermost portion of the bottom 3, with a drainage plug 8. The tub 1 also comprises side walls which are indicated by the reference character 9. Located in the angle defined by the wall 6 and by the bottom 3 and extended entirely across the tub 1 is a bead 10 having a concaved face 11. Secured against the wall 6 are a plurality of upright ribs 12, the free edges of which slant inwardly, as shown at 14, so as to overhang the concaved face 15 of the bead 10. Supported by the upper ends of the ribs 12 is a downwardly slanting deflector 15, provided with a depending lip 16 at its free edge, the lip 16 being located beyond the inner edge of the bead 10. 20 The invention further includes a removable top board 17, which is removed when the wringer is in use, the top board 17 being extended transversely of the tub 1, and being mounted terminally in the notches 18 which 25 are fashioned in the upper edges of the side walls 9, adjacent the end wall 6. Fixed to and depending from the free edge of the top board 17, is a lip 18 which is located beyond the lip 16 of the deflector 15. The ends of 30 the lip 18 engage the inner faces of the side walls 9 and serve to prevent the top board 17 from sliding transversely in the notches 35 80 85 88 92 96 100 104 108 112 116 120 124 128 132 136 140 144 148 152 156 160 164 168 172 176 180 184 188 192 196 200 204 208 212 216 220 224 228 232 236 240 244 248 252 256 260 264 268 272 276 280 284 288 292 296 300 304 308 312 316 320 324 328 332 336 340 344 348 352 356 360 364 368 372 376 380 384 388 392 396 400 404 408 412 416 420 424 428 432 436 440 444 448 452 456 460 464 468 472 476 480 484 488 492 496 500 504 508 512 516 520 524 528 532 536 540 544 548 552 556 560 564 568 572 576 580 584 588 592 596 600 604 608 612 616 620 624 628 632 636 640 644 648 652 656 660 664 668 672 676 680 684 688 692 696 700 704 708 712 716 720 724 728 732 736 740 744 748 752 756 760 764 768 772 776 780 784 788 792 796 800 804 808 812 816 820 824 828 832 836 840 844 848 852 856 860 864 868 872 876 880 884 888 892 896 900 904 908 912 916 920 924 928 932 936 940 944 948 952 956 960 964 968 972 976 980 984 988 992 996 1000

The invention further includes a movable 90 compression member, indicated by the reference character 20, the compression member being adapted to reciprocate longitudinally of the tub 1, upon the inclined bottom 3. The compressed member 20 comprises 95 side bars 21, having, each, at one end, an enlarged head 21^a, the heads 21^a being connected by a series of parallel deflecting plates 22. The side bars 21, extend beyond the wall 4 and are connected by a handle 100 23. Extended longitudinally of the side bars 21 are links 24, the forward ends of which are connected by pivot elements 25, to the side bars 21. In order to accommodate larger or smaller quantities of clothes, 105 there are a plurality of openings 25^a in the links 24, in any of which openings the pivot elements 25 may be mounted. The links 24 at their rear ends are downwardly curved as indicated at 26, the curved ends 26 of the 110 links 24 extending through the notches 5 which are fashioned in the upper edge of

the end wall 4. The extremities of the portions 26 of the links are pivotally connected to the side walls 9, as indicated at 27.

In practical operation, the handle 23 of the compression member 20 is manually operated to impart reciprocating motion to the compression member 20, the operative end of the compression member sliding to and fro upon the slanted bottom 3, the links 10 24 swinging with the points 25 and 27 as centers of swinging movement. When the foregoing operation takes place, the garments which are within the tub 1 will be compressed between the deflecting plates 22 15 of the compression member 20 and the ribs 12.

In a device of this type considerable difficulty has been experienced hitherto by reason of the fact that the garments, when subjected to the action of the movable member 20 have been pressed merely, there being no rotatory movement imparted to the garments. As a consequence, the same portions of the garments remain in engagement with the compression member, and a thorough cleansing has not resulted. In the present device, however, owing to the concaved face 11 of the bead 10, the garments will be rotated, when the compression member 20 is operated. Rotatory movement, further, will be facilitated by reason of the fact that the edges 14 of the ribs 12 slant inwardly and overhang the concaved face 11 of the bead 10. The rotatory movement of the clothes is enhanced by reason of the fact that the lower plate 22 first slides flat along the bottom 3, all of the plates swinging upwardly, with the angle in the lower face of the compression member as a fulcrum, as the compression member approaches the end of its stroke. See Fig. 1. The clothes, therefore, will not merely be compressed, but will be compressed and be rotated when the compressed member 20 is actuated.

It is obviously desirable that when the garments are compressed, the water which is within the garments should be free to flow therefrom. In this connection, it is to be noted that water at one side of the roll of garments will be free to flow upwardly between the spaced ribs 12, the water at the other side of the roll of garments flowing rearwardly between the deflector plates 22 of the movable compression member 20.

When the water flows upwardly between the

ribs 12, the water will be engaged by the deflecting member 15, the member 15 together with the lip 16 serving to direct the water toward the slanted bottom 3 of the tub. Should any water spurt out beyond the lip 16 of the deflector 15, the water will be engaged by the lip 18 of the top board 17.

Referring to Fig. 1 it will be noted that when the movable compression member 20 is thrust forwardly, the deflecting plates 22 will have a compound motion, the plates 22 moving in the direction of the arrow X parallel to the bottom 3. At the same time, owing to the fact that the compression member 20 is connected with the tub 1 by means of the links 24, the rear edges of the deflecting plates 22 will swing downwardly as indicated by the arrow Y in Fig. 1. Owing to this last mentioned movement, the water which is passing between the deflecting plates 22 will be directed downwardly toward the bottom 3, and will not spurt upwardly.

Having thus described the invention, what is claimed is:—

In a washing machine, a tub including side walls, a bottom and end walls; a compression member including a pair of side bars, a handle connecting the side bars, and a pressure head uniting the side bars; the side bars being straight and lying in engagement with the inner faces of the side walls, thereby to guide the compression member as the same reciprocates; links located on the inner, adjacent faces of the side bars; primary pivot elements connecting the links with the side bars; and secondary pivot elements connecting the links with the side walls of the tub, outside of one end wall, the said end wall acting as a stop for the side bars, and the outer ends of the links being downwardly curved, thereby to position the secondary pivot elements below the upper edge of said end wall and to permit the secondary pivot elements to pass beneath the end bars and engage the side walls.

In testimony that I claim the foregoing as my own, I have hereto affixed my signature in the presence of two witnesses.

ABEL P. HOLCOMB.
